UNITED STATES PATENT OFFICE.

WILLIAM H. HUGG, OF ELIZABETH, NEW JERSEY, ASSIGNOR TO THE SINGER MANUFACTURING COMPANY, A CORPORATION OF NEW JERSEY.

LOOPER-CARRIER FOR SEWING-MACHINES.

1,252,696.

Specification of Letters Patent. Patented Jan. 8, 1918.

Application filed November 6, 1914. Serial No. 870,552.

To all whom it may concern:

Be it known that I, WILLIAM H. HUGG, a citizen of the United States, residing at Elizabeth, in the county of Union and State of New Jersey, have invented certain new and useful Improvements in Looper-Carriers for Sewing-Machines, of which the following is a specification, reference being had therein to the accompanying drawings.

10 This invention relates to that class of plural-needle sewing machines particularly of the chain-stitch type for producing simultaneously two or more parallel seams wherein the lateral spacing apart of the needles 15 is determined by the particular nature of the work to be performed. It has for its object to provide an effective looper-carrier adapted to sustain a plurality of loopers of uniform shape and size for all gages 20 in which the needles are set, the loopers receiving their endwise or loop-seizing movements in a direction approximating parallelism with the plane in which the needles are set and transversely of the direction of feed of the work.

According to the present improvement, the looper-carrier comprises two looper-supporting members having a common fulcrum upon which they receive their rocking loop-seizing and shedding movements upon which they are relatively adjustable endwise of the looper-blades, means being provided for securing such members together in their requisite positions to locate the points of 35 the respective looper-blades a distance apart equal to the spacing apart of the needles with which they coöperate. One of the looper-supporting members is preferably formed with a boss upon which the other 40 member is coaxially mounted for circular adjustment and which boss is adapted to receive the common fulcrum-pin upon which the loopers perform their operative movements.

45 In the accompanying drawing, Figure 1 is an end elevation of the looper embodying the present improvement, with two loopers sustained thereby for coöperation with laterally spaced needles carried by a common 50 needle-bar in a manner well known. Fig. 2 is a perspective view of the looper-carrier and loopers upon a larger scale. Figs. 3 and 4 are side elevations of the parts represented in Fig. 1, but showing the needles 55 and loopers set at different gages.

The looper-carrier is shown comprising what may be termed primary and auxiliary looper-supporting members 1 and 2, the former having at its lower end the boss 3 reduced at one extremity to form the shoulder 60 bearing portion 4 upon which is fitted the apertured lower end of the auxiliary looper-supporting member 2. The auxiliary member 2 is shown formed with a slot 5 concentric with the bearing 4 to receive the shank 65 of the clamp-screw 6 tapped into the looper-supporting member 1 and adapted to clamp the two members together in their desired position of adjustment around the axis of the bearing 4.

70 Within the axial aperture of the boss 3 is secured the fulcrum-pin 7 having the head 8, upon which the compound looper-carrier thus formed performs its rocking movements. The primary looper-supporting 75 member is formed in its upper portion with a lateral socket in which is secured by means of the set-screw 9 the flattened cylindrical shank 10 of the ball-stud 11 adapted for connection with the actuating means from 80 which the looper-carrier derives its rocking movements.

The members 1 and 2 have at their upper 85 ends the usual sockets in which are secured by means of set-screws 12 the shanks of loopers 13 and 14 of well-known form, with flat blades 15 and 16 having lateral thread-grooves 17 terminating adjacent the looper-points 19 and 20 in thread-eyes 18. Each looper-blade is shown formed at the heel 90 with an aperture 21 in communication with a threading slit 22 at the upper edge of the blade, the body of the looper 14 having secured thereon the plate 23 formed with open guide-eyes 24 through which the 95 threads are directed to the respective loopers.

The looper-blades coöperate with laterally spaced eye-pointed needles 25 and 26 secured in the multiple needle-clamp 27 carried by the reciprocating needle-bar 28 in the usual 100 manner. The needles are spaced apart a distance corresponding to the gage of the seam to be produced, and one is set in advance of the other a distance equivalent to the spacing apart of the looper-blades, as represented in the drawing.

In Fig. 3 a comparatively narrow-gage needle-clamp 27 is employed, the component members of the looper-carrier being so adjusted circularly upon their common ful- 110

crum-stud 7 that the points 19 and 20 of the looper-blades are spaced correspondingly with the needles and with the spacing apart of the parallel seams to be produced, the members 1 and 2 of the looper-carrier being secured in such adjusted position by means of the clamp-screw 6. In Fig. 4 the needle-clamp 27' is shown of a much wider gage, and the component members of the looper-carrier are accordingly adjusted to bring the looper-points the same distance apart lengthwise of the looper-blades as the needles.

In order that the loopers shall properly coöperate with the needles, it is important that each should enter the thread-loop of its respective needle at the same instant and at the same distance above the eye of the then ascending needle. In practice the looper-blades are bowed substantially concentrically with the axis of their operative or loop-seizing and -shedding movements. According to the present improvement, the looper-blades are relatively adjustable concentrically with the fulcrum upon which they perform their operative movements, and therefore in all adjustments they bear practically the same relation to the needles and the work. Thus they are caused to seize the needle-thread loops in the most advantageous positions of the respective needles and to manipulate said loops in the completion of a stitch-forming cycle under precisely the same conditions in their relation to the work to which the needle-thread loops are attached and the feed of the work.

In order to secure exact uniformity in the relation of the loopers with the needles and the throat-plate, or the work sustained thereby, for different gages of seam, it has heretofore been deemed necessary to employ different sets of loopers for each gage of seam, but according to the present improvement, the two parts of the looper-carrier are relatively adjustable in such manner that the points and heels of a single set of looper-

blades of permanent design are invariably at the proper distance from their axis of oscillation, regardless of the distance apart of the looper-points lengthwise of the looper-blades.

Having thus set forth the nature of the invention, what I claim herein is:—

1. A multiple looper-carrier comprising a primary looper-supporting member, a fulcrum therefor, an auxiliary looper-supporting member fulcrumed coaxially with the primary member, and means for securing said members together adjustably around said fulcrum, whereby in all adjustments of said members the looper-blades mounted thereon are caused to bear the same relation to the needles and the work.

2. A multiple looper-carrier comprising a primary looper-supporting member formed with a boss to receive a fulcrum-pin, an auxiliary looper-supporting member apertured to fit said boss upon which it is circularly adjustable, and means disposed eccentrically to said boss for securing said members together in different positions of adjustment, whereby in all adjustments of said members the looper-blades mounted thereon are caused to bear the same relation to the needles and the work.

3. A pivoted looper carrier, a looper fixed to said looper carrier, said looper carrier having a projecting flange concentric to the axis of the looper carrier, a looper support having an opening which receives said flange and a slot, a set-screw passing through said slot into the looper carrier for holding the support in adjustable positions, and a looper fixed to said support.

In testimony whereof, I have signed my name to this specification, in the presence of two subscribing witnesses.

WILLIAM. H. HUGG.
